UNITED STATES PATENT OFFICE

145,230

DESIGN FOR A CARPET OR THE LIKE

Earl C. Schmidt, Philadelphia, Pa., assignor to Hardwick & Magee Company, Philadelphia,
Pa., a corporation of Pennsylvania

Application January 7, 1946, Serial No. 125,337

Term of patent 7 years

(Cl. D92—4)

To all whom it may concern:

Be it known that I, Earl C. Schmidt, a citizen of the United States, residing in Philadelphia, county of Philadelphia, State of Pennsylvania, have invented a new, original, and ornamental Design for a Carpet or the Like, of which the following is a specification, reference being had to the accompanying drawing forming part thereof, in which the figure is a face view of a portion of a carpet or the like, showing my new design. The broken lines outline substantially a design unit, which unit is repeated in regular succession as indicated by the extensions beyond the unit boundaries.

I claim:

The ornamental design for a carpet or the like, as shown and described.

EARL C. SCHMIDT.
